SAMUEL E. WINSLOW, OF LEICESTER, MASSACHUSETTS.

SKATE.

Application filed December 4, 1926. Serial No. 152,696.

My invention is an improved bracket for use in a skate which is stiffened against vertical, longitudinal and transverse strains applied to the foot plates and their supporting posts, by braces applied to the sides of the posts connecting the runner with the foot plates. The connection is achieved by the use of a pair of solid semi-spherical brackets, depending from a heel- or toe-plate, which are connected to the reinforced posts by a bolt or rivet passing through the opposed brackets and the upper end of a reinforced post held between the opposed brackets.

It is a matter of some difficulty to connect such parts without possibility of the parts loosening somewhat under the strains of use, without expensive milling or fitting operations, to ensure at the outset a close fit between the opposed parts, the function of the bolt or rivet being largely to hold the fitted parts in close engagement.

I have devised a new method of forming and fitting the solid brackets which ensures a perfect fit between the opposed parts without milling or fitting operations at a great saving in labor cost without any sacrifice of appearance or strength, over a similar bracket machined to get the desired close fit.

In the drawings:

Figure 1 is a side elevation of skate;
Figure 2 is a cross-section on line 2—2 of

Figure 1;

Figure 3 is a cross-section on line 3—3 of
Figure 1;

Figure 4 is a fragmentary plan view, on an enlarged scale, of one end of the blank from which the horizontal stiffening element is formed;

Figure 5 is a perspective view on an enlarged scale, of one of the reinforce elements.

The blade in my improved device is formed, as is common, of a horizontal runner A, perpendicular to which are four integral posts a' , a^2 , a^3 , a^4 . To the upper or free ends of these posts are secured a toe-plate, preferably in two parts, B, each part of which is provided with depending brackets, b and 1 and a heel plate, preferably in two parts D each part of which is provided with depending brackets d and 1 .

The posts a' , a^3 , respectively beneath the ball of the foot and the front of the heel

are subject to great transverse strains as well as most of the vertical pressure due to the weight of the skater. I have found that the ordinary post, integral with the blade, such as the front and rear posts, a^1 , a^4 , is not adapted to endure the transverse strains of the medial position and preserve perfect alignment with respect to the foot plates and the straightness of the blade A itself and this is especially true when, as is desirable, the blade is thin and therefore flexible.

To correct this difficulty I provide posts a^2 , a^3 , with side reinforcing elements 2, which lie on either side of posts a^2 , a^3 , from the upper or free end of the posts to and below the junction of the posts with the blade A and these are preferably spot welded to the posts and blade so as to become in effect integral therewith. These reinforcing elements are preferably shaped as shown in Figures 3 and 5, with a plane face to fit against the flat side of a post a^2 , or a^3 , and a convex face outwardly.

The upper edges of the element 2 are preferably recessed, as shown at 2^a (Figure 5) and are provided with an aperture 2^b . The aperture 2^b registers with an aperture in the upper end of a post a^2 , a^3 . This aperture through the upper ends of the elements 2 and posts a^2 or a^3 is to receive a clamping bolt or rivet 1^b passing through the brackets 1.

The brackets b and 1 are such as have heretofore been in use in connecting the front end of a toe-plate with the front post and the rear end of a heel-plate with the rear post. The depending brackets 1 are at the outset hollow concavo-convex segments of a sphere, and are so shaped in order to provide necessary space for the reinforced upper ends of the runner posts a^2 , a^3 .

The reinforcing members 2 being applied to posts a^2 , a^3 , and fixed in place, by spot welding, riveting or other suitable method, the longitudinal stiffening member E is applied by passing apertures, e , in the blank E over the free ends of the posts and securing the two edges of the member E together preferably by rivets e' passing through suitable apertures e^2 in the edges of member E and in the blade A (see Figures 1, 2 and 4). The toe and heel plates are next mounted upon their respective posts, a^1 , a^2 and a^3 , a^4 , and the brackets b , d , are

- riveted thereto by rivets b' d' passing through suitable apertures in the brackets and the upper end of posts a^1 , a^4 , and the brackets 1 are connected by means of a rivet 5 1^b passing through aperture 2^b in the reinforces 2 and a suitably registering aperture in the upper ends of posts a^2 , a^3 . The hollow interior of the brackets 1, after they are suitably placed, is filled with molten metal F of suitable character which sets in the interior upon cooling, fitting and connecting with perfect accuracy all the contained parts. I have used with success solder. The edges of brackets 1 are wiped down into recesses 2^a of the reinforces 2, the edges of bracket 1 butting against the sides of the posts a^2 , a^3 , to form a finished looking article when suitably plated (see Figure 3).
- 20 It will be apparent from the foregoing that the brackets 1, when filled with solid metal, will fit accurately the contained parts, i. e., rivet, posts and reinforces, and will hold these parts in fixed relation, the rivet being called upon to restrain only any possibility of a separation of the two parts of the bracket 1.

While I have, in this description specified metal as the filler, because I have no knowledge or experience of any other material that is suitable, I desire to cover other materials, if any, which might be flowed into the bracket cavity and therein harden, the gist of the invention in this aspect being the 30 filling of the cavity with molten material 35

to harden and thereafter connect the parts of bracket within and without.

I claim:

1. In a skate, a blade; integral posts extending upward from the blade; reinforcing side pieces fast to the blade and posts; heel and toe plates, carrying hollow depending segmental brackets, the hollows of the brackets being opposed to receive the upper ends of the reinforced posts; a connecting bolt through brackets, reinforces and post; a metallic filler element shaped to fit exactly all surfaces within the hollow bracket. 40
2. In a skate, a blade; integral posts extending upward from the blade; reinforcing side pieces fast to the blade and posts; heel and toe plates, carrying hollow depending segmental brackets, the hollows of the brackets being opposed to receive the upper ends of the reinforced posts; a connecting bolt through brackets, reinforces and post; a filler element shaped to fit exactly all surfaces within the hollow bracket. 45
3. In a skate, a blade; integral posts extending upward from the blade; heel and toe plates, carrying hollow depending brackets to receive the upper ends of the posts; a connecting bolt through brackets and posts; a filler element shaped to fit all 50 surfaces within the hollow bracket. 55

Signed at Worcester, Massachusetts, this third day of December, 1926.

SAMUEL E. WINSLOW.
